(57) **CLAIM**

The ornamental design for an electrical connector, as shown and described.

DESCRIPTION

FIG. 1 is a front elevational view of an electrical connector; FIG. 2 is a rear elevational view thereof; FIG. 3 is a right side elevational view thereof; FIG. 4 is a top plan view thereof; FIG. 5 is a bottom plan view thereof; and, FIG. 6 is an enlarged cross-sectional view thereof along a line 6—6 in FIG. 1; and, FIG. 7 is a front, top, and right side perspective view thereof. A left side elevational view of the electrical connector is omitted because it is presented symmetrical to the right side elevational view of FIG. 3.
